(57) **CLAIM**

We claim the ornamental design for a laundry appliance, as shown and described.

DESCRIPTION

FIG. 1 is a front perspective view of the laundry appliance showing our new design;

FIG. 2 is a front elevational view of the laundry appliance of FIG. 1, but with the lower base portion of the broken line environmental structure seen in FIG. 1 removed;

FIG. 3 is a side elevational view, the opposite side being a mirror image thereof;

FIG. 4 is a top plan view thereof; and,

FIG. 5 is a bottom plan view thereof.

The broken lines depict environmental structure and portions of the laundry appliance that form no part of the claimed design.
